UNITED STATES PATENT OFFICE.

WENDELL L. CARLSON, OF WASHINGTON, DISTRICT OF COLUMBIA.

AMPLIFIER.

Application filed August 17, 1922. Serial No. 582,450.

My invention relates generally to radio frequency amplifiers and more particularly to stabilizing the action and effectiveness of such amplifiers. 55

the impedance coupler both of which simply impress the alternating plate potential of one tube directly on the grid of an associated tube. Second the transformer coupler

5 An object of the invention is to provide an amplifier in which the tendency to oscillate is reduced to a minimum.

Another object is to increase the amplifying range over a wide band of frequencies.

10 Heretofore it has been found necessary to take special precautions to prevent the amplifier from oscillating locally, or "howling", by such means as connecting adjustable bias potentials to the grids of certain of
15 the amplifying tubes, or other such similar arrangements, but with the present invention the transformer characteristics are made quite uniform throughout their frequency range.

20. A further object of the invention is to provide a transformer construction which will not amplify impulse energy such as static to a greater degree than the less damped signal energy.

25 A still further object is to embody certain new combinations in the construction of inter-valve radio frequency transformers so as to allow the amplifier to operate with the utmost reliability without impairing its
30 amplification characteristic.

With the above and other objects in view the invention consists in the combination, construction and arrangement of parts as will be hereinafter fully described.

35. Reference is to be had to the accompanying drawings forming a part of this specification in which like reference characters indicate corresponding parts throughout the several views, and in which—

40 Figure 1 is a schematic diagram of a circuit employing three stages of amplification and a detector with resistance wound inter-stage and inter-valve transformers,

45 Fig. 2 is a modification of the radio transformer construction employing a short circuit winding,

Fig. 3 shows certain transformer characteristics plotted graphically, and

Figure 4 is a modification of the radio transformer construction employing separate resistances in series with the windings.

Heretofore it has been customary to obtain inter-valve coupling by two general methods. First the resistance coupler and

methods. First are resistance coupler and

the impedance coupler both of which simply impress the alternating plate potential of one tube directly on the grid of an associated tube. Second the transformer coupler which transfers potential in the grid circuit of a second tube by magnetic coupling. This invention relates only to inter-valve transformers.

Referring more particularly to Figure 1 of the drawings, the antenna primary circuit 5 is tuned to the incoming radio frequency signal. 6 is a secondary tuned circuit coupled to the primary circuit and connected to the grid *g* and filament *f* of the vacuum tube 7. The plate *p* of the tube is connected through the transformer primary winding 8 of the transformer T to a plate battery *b*. The winding 8 is magnetically coupled by the laminated iron core 9 to the secondary winding 10. The primary and secondary windings 8 and 10 are constructed of high resistance wire in order of 10 to 20 times the resistance of an equivalent copper wire construction. For the purpose of illustrating schematically the transformer windings the inductance and resistance of the windings are shown separately and are represented respectively by 8^a and 8^b for the primary and 10^a and 10^b for the secondary winding. The secondary winding 10 is connected to the input of tube 11. In like manner the tubes 11 and 12 are coupled to the inter-valve transformer 13. Tube 12 is also connected through transformer 14 with the detector tube 15, which has a telephone receiver 16 connected in its output circuit. The customary grid leak 17 and stopping condenser 18 are interposed in the grid circuit of the detector tube 15. Individual filament batteries *a* and plate batteries *b* may be employed, but it is desirable to work the amplifier on one battery unit.

In the modification shown in Fig. 2 the primary and secondary windings 8 and 10 respectively are wound with standard copper or highly conductive wire on lamination 9. 100 The coil 19 represents a short-circuited turn of copper wire in the magnetic field of the transformer.

In the modification shown in Fig. 4, the windings 8 and 10 on core 9 are of ordinary copper or highly conductive wire but have resistances 21 and 20 inserted in series with these windings. 105

- In Fig. 3 the characteristic curves of two radio frequency transformers are plotted with relative voltage output as ordinate against wave length in meters as abscissa.
- 5 Curve A is of a transformer employing copper wire windings of low resistance and an iron core and curve B is an identical transformer construction with the exception that resistance wire windings are employed.
- 10 The double hump or two resonant peaks shown are due to employing iron cores.
- The operation of the amplifier circuit of Figure 1 is as follows: A modulated radio signal impressed on the tuned antenna circuit 5 is transferred to the tuned coupled circuit 6 and thence to the first amplifying tube 7. Tubes 7, 11 and 12 are actuated successively by the signal energy. The amplification is governed by the tube constants 20 and the inter-valve transformer characteristics at the frequency of the signal being received. The signal is rectified in tube 15 and the modulated component actuates the telephones 16.
- 25 In radio frequency amplifiers there is a decided tendency for the individual stages to oscillate locally and for the several stages to oscillate collectively. These oscillations are caused by capacity coupling between the 30 high potential terminals of the circuit; resistance coupling in the common battery circuit; and irregular transformer output voltage characteristics. Shielding the amplifier circuit is effective in reducing the capacity 35 couplings of the circuits materially and radio frequency choke coils in the low potential side of the common battery circuit, when a common plate battery is used, are sometimes employed to eliminate the resistance 40 coupling effect.
- Even with these precautions an amplifier employing inter-valve transformers with characteristics as shown in curve A, Fig. 3, is likely to oscillate locally at say 210 meters 45 which corresponds to the frequency at which the transformer responds most efficiently. In such cases it is necessary to decrease the tube amplification to the point where oscillations cease. Usually this is accomplished 50 by varying the bias potential from a potentiometer, which is generally called a stabilizer. It is not desirable from an operating standpoint to employ more than one variable stabilizer adjustment and, if several 55 stages are connected to the same stabilizer, the adjustment can be made correct for only one stage of amplification due to the variable characteristics of the tubes and slight irregularities in each transformer. In some 60 cases, it is found necessary to provide fixed grid potential of some such valve as to decrease tube amplification. Such a procedure will greatly impair the amplification obtained on wave lengths off resonance such as 65 300 meters when employing transformers

with characteristics as represented by curve A.

For these reasons iron core transformers are not used in radio frequency amplifiers, and failure to use iron cores prevents obtaining amplification over a wide range of frequencies as may be obtained when a double-humped amplification characteristic, as illustrated by curves A and B, Fig. 3, is used. My invention makes it possible 75 to use iron cores, thus obtaining the wide range amplification due to the double-humped characteristic obtainable in such a transformer. The series resistance or apparent resistance cuts down the resonance 80 voltage peaks and, in some cases, increases the valley voltages, thus giving a more uniform output voltage throughout the transformer frequency range with a constant input, and at the same time the tendency to 85 oscillate or "howl" is offset.

It is found in amplifiers employing transformers with characteristics as graphically illustrated by curve B in Fig. 3 that the correct grid bias voltage can be employed on all tubes for all frequencies throughout the amplifier's wave length range thus obtaining the maximum voltage amplification from each tube. It should be understood that curves A and B are of individual transformers and that if the amplifier of Figure 1 were to employ transformers with curve A characteristics, it would be necessary to provide adjustable biases on the grids of successive tubes so as to reduce the amplification below the threshold oscillating value. The amplification would thus be about the same as obtained with an amplifier employing 95 transformers with curve B characteristics.

It has been found that with resistance winding transformers, or equivalents, that the highly damped impulses; that is, static interferences, are not amplified to any greater degree than the signal energy, while with a transformer whose characteristics are 110 similar to curve A and when operating on a signal say at 300 meters, the impulse energy will be amplified to a greater degree than the signal.

It has been found practical to employ low resistancce primary and secondary winding with a short circuited turn in the magnetic path, Fig. 2, or resistance in series with the windings, Fig. 4. These constructions are equivalent to employing resistance wire since they increase the effective resistance of the transformer and, therefore, have the same effect of reducing the transformer resonant peaks as when employing resistance wire.

It is understood that the above description and accompanying drawings comprehend only the preferred embodiment of my invention and that various minor changes in details of construction, proportion, and arrangement of parts may be resorted to 125 130

within the scope of the appended claims and without sacrificing any of the advantages of my invention.

Having fully described my invention, what I desire to secure by Letters Patent is:-

1. In an amplifying transformer for radio frequency currents, an iron core, primary and secondary windings upon the iron core, the primary and secondary windings consisting of low resistance wire and means in

series with at least one of the windings for increasing its resistance.

2. In an amplifying transformer for radio frequency currents, an iron core, primary and secondary windings upon the iron core, the primary and secondary windings consisting of low resistance wire and means in series with each of the windings for increasing the effective resistance of each winding.

WENDELL L. CARLSON.
